(57) CLAIM

We claim the ornamental design for a lubricant dispenser, as shown and described.

DESCRIPTION

FIG. 1 is a right side anterior perspective view of a lubricant dispenser.

FIG. 2 is an anterior view a lubricant dispenser.

FIG. 3 is a posterior view a lubricant dispenser.

FIG. 4 is a right side view of a lubricant dispenser.

FIG. 5 is a left side view of a lubricant dispenser.

FIG. 6 is a top view of a lubricant dispenser; and,

FIG. 7 is a bottom view of a lubricant dispenser.

The broken lines shown are included for the purpose of illustrating portions of the lubricant dispenser that form no part of the claim.
